UNITED STATES PATENT OFFICE.

CHARLES VAN AMBURGH, OF TACOMA, WASHINGTON, ASSIGNOR TO AMERICAN SMELTING & REFINING COMPANY, A CORPORATION OF NEW JERSEY.

CONVERTER HOOD.

1,417,588.

Specification of Letters Patent. Patented May 30, 1922.

Application filed July 21, 1917, Serial No. 181,968. Renewed September 26, 1921. Serial No. 503,383.

To all whom it may concern:

Be it known that I, CHARLES VAN AMBURGH, a citizen of the United States, and resident of Tacoma, in the county of Pierce and State of Washington, have invented 5 certain new and useful Improvements in Converter Hoods, of which the following is a specification.

My invention relates in general to an improvement in the connection between a 10 movable metallurgical furnace and its permanently fixed gas discharging stack and specifically relates to a converter hood and its associated parts.

15 One of the objects of the invention is to provide a connection between the converter and hood which will have the least possible clearance and which will maintain a substantially gas tight connection between the 20 converter and hood under all working conditions.

Another object of the invention is to provide a connection which will in no way interfere with the normal operation of the 25 converter and which will automatically clear itself of any accretions which may form during the blowing or other operations incidental to the use of the device.

Still another object of the invention is to 30 provide a conveniently positioned opening for charging the converter without removing the hood and to provide a simple control for simultaneously actuating a closure means for said opening and for controlling the gas flow through the hood.

Various other objects and advantages of the invention will be in part obvious from an 35 inspection of the accompanying drawings and in part will be more fully set forth in 40 the following particular description of one form of mechanism embodying my invention, and the invention also consists in certain new and novel features of construction and combination of parts hereinafter set 45 forth and claimed.

Referring to the accompanying drawings:

Figure 1 is a view in side elevation of one 50 of a series of converter units in a smelting plant, the several units of which discharge their gaseous products into a conduit herein shown in section;

Figure 2 is a front elevational view of a portion of the device shown in Figure 1;

Figure 3 is a transverse sectional view taken on the line 3—3 of Figure 1 looking 55 in the direction indicated by the arrow;

Figure 4 is a vertical sectional view taken on the line 4—4 of Figure 2 looking in the direction indicated by the arrow;

Figure 5 is a detailed front elevational 60 view of a portion of the movable closure and its operating mechanism; and

Figures 6 and 7 are each transverse sectional views taken respectively on the lines 6—6 of Figure 1 and 7—7 of Figure 2; 65

In the following description and in the claims, parts will be identified by specific names for convenience of expression but they are intended to be as generic in their application to similar parts as the art will 70 permit.

Referring to the drawings, there is shown in general a conventional form of rotary converter 10, designed in one position to discharge its gaseous products into a relatively 75 fixed hood 11 leading to a conduit 12 which may lead to the stack or bag house as is usual in plants of the character suggested.

The converter includes a cylindrical shell 13 (see Figure 4) mounted to rotate about 80 its horizontally disposed axis and driven from a motor 14 through a gear drive 15, while the shell is resting on roller cradles 16, all as is usual in one well-known form of such devices. The cradle in this disclosure differs from the conventional form of such converter supports in that the shell engaging rollers 17 are mounted in pairs on rocking frames 18 pivotally mounted to the supporting base 19 to automatically adjust the 90 position of the rollers so that they may respond to distortion in the shell or shifting of the axis of rotation of the same while actively working. The shell is provided with an opening 20 in the side thereof 95 adapted in one position of the converter to open into the hood during the blowing operation, or to receive the charge fed into the hood opening 21 hereinafter more fully described, or when rotated into a discharging 100 position to pour its contents onto the platform p. The opening 20 is centrally disposed

is shown in Figure 2 and is defined on opposite longitudinal sides by a pair of rings 22 which encircle the shell and extend outwardly therefrom for some material distance 5 in order to provide a support for the lower end of the hood 11. The front and rear sides of the opening are outlined by upstanding walls 23 (see Figure 4) which contact with the connecting portions of the rings 10 22 to form a converter stack carried by and extending radially outward from the shell 13. The converter stack projects centrally through a curved closure plate 24 which has a curvature with its center coincident with 15 the axis of rotation and extending forwardly and rearwardly of the converter stack so as to project for some material distance in each direction beyond the front and rear sides of the hood 11 as shown more particularly in 20 Figure 4.

The hood is of a conventional form with its lower portion substantially square in cross section as shown in Fig. 6 and with its upper reduced end 25 cylindrical as shown in Fig. 3. The upper end is loosely fastened to and opening into the conduit 12. The weight of the hood is supported mainly from cleats 26 (see Fig. 1.) on opposite sides of the hood which rests loosely upon supporting bars 27 carried by the main supporting frame 28. It is preferable however, to consider that a material portion of the weight of the hood is supported directly on the rotatable converter shell and particularly upon the hood carrying rings 22. This supporting connection is provided by means of two sets of rollers 29 mounted on each side of the hood, each set of which is mounted at opposite ends of equalizing arms 30 each pivoted intermediate its length to a cleat 31 fastened to the side of the hood and coacting with the other cleats to reinforce the lower portion of the hood against distortional strains. As the rings 22 are of some material depth it is apparent that this form of mounting will tend to maintain the lower portion of the hood in spaced relation to the converter shell, so that distortion of the shell, due to the heat and other conditions present, will have little, if any, effect upon the position of the hood. In this way the hood will be maintained substantially in fixed position under all working conditions. As the converter adjusts itself on its roller cradle support, the hood supporting rollers 29 will likewise adjust themselves so that a smooth running converter is provided under all conditions of service and at the same time the connection with the hood is maintained.

65 The lower front side of the hood is cut away to provide the opening 21 through which the converter may be charged when the conveyer is in position to open the stack towards said opening. The opening is pro-

vided with a movable closure 33 by means of which the opening is closed and a substantially air tight connection is provided thereby between the front portion of the hood and the adjacent forwardly extending portion of the cover plate 24. The closure 33 includes a frame formed of a pair of cable segments 34 mounted on opposite sides of the hood above the opening 21. To the forward of each of these cable segments is attached a cable 35 trained over a cable sheave 36 supported by a part of the main frame 28. Each cable is then passed down about a differential drum 37, both of which drums are mounted upon a drum shaft 38 capable of receiving power from some suitable source designed to rotate the drums in either direction. Counterweights 39 are suspended from the free ends of each of the cables so as to counterbalance substantially the weight of the closure and its attached parts. The closure frame also includes a pair of parallel arms 40 pivoted to cleats 41 on opposite sides of the hood below and forwardly of the cleats 42 which form the pivotal support for the cable segments 34 all as shown particularly in Figure 1. The cable segment on each side of the hood is connected to its adjacent parallel arm by means of an arch beam 43 which in turn supports a series of ribbed cover plates 44 coacting to form a plate curved to conform to the configuration of the sides of the hood forming the opening 21.

A front curtain plate 45 is hung from the 100 rod 46 connecting the parallel arms and engages the front portion of the cover plate 24 when the closure is in position closing the opening 21 as shown in full lines in Figures 1 and 2. This curtain plate is preferably 105 formed of slats 47 pivotally connected in order by links 48, as shown more particularly in Figure 5.

A similar back curtain plate 49 is hung from the rear edge of the hood and engages the rear portion of the cover plate so as to maintain a substantially air tight connection between the rear portion of the hood and the cover plate. It is noted that these curtains are hung so that they may be moved outward. In this way any accretion which may have accumulated on the portion of the cover plate within the hood is dumped therefrom when the converter is rotated into its discharging position. 110 115 120

The reduced portion 25 of the hood is provided with a damper 50 (see Fig. 3) which obviously may be controlled directly by manual means or as shown in this disclosure, the damper may be connected with the mechanism which operates the closure 33 so that when the closure is moved into position to uncover the opening 21 the damper is automatically moved into closing position thus preventing any back discharge 130

from the conduit 12. For this purpose a damper lever 51 is fixed to the damper shaft 52 and is connected by a pair of parallel rods 53 with a similar lever 54 fixed to one of the cable segments 34.

In operation it will be understood that in order to charge the converter it is moved into the position shown in Figures 1 and 4 and by actuating the shaft 38 controlling the differential drums, the closure 33 is moved from the full line position shown in Figures 1 and 2 into the open position shown in full lines in Figure 4 and shown in dotted lines in Figure 1. The converter is charged through the opening 21 and by reversing the actuation of the shaft 38 the closure is moved into its position covering the opening 21. This closing of the cover will automatically move the damper into the open position shown in dotted lines in Figure 1 and the blowing or other metallurgical operation may be practiced as is usual with such devices. During this actuation of the converter the curtain plates from the hood will be in close engagement with the cover plate carried by the converter, so that little, if any, air will be drawn into the hood from the outside of the converter. When it is desired to dump the charge from the converter, it is rotated through the actuation of the power member 14 as is usual with such devices. During this rotation it will be apparent that the lower end of the hood will ride on the converter without in any way effecting its normal operation.

By means of a device of this character, it is possible to provide a converter hood with minimum clearance and which will in no way interfere with converter operations. All gases produced by the converter will be taken up by the flue and stack system represented by the conduit 12 with the least possible strain on the capacity thereof and further there will be an elimination of surface gases about the converter plant, which elimination acts to increase flue and stack capacity. Further any distortion which may take place due to the heating of the converter shell will have no effect upon the positioning of the hood, so that racking action of this large member is practically eliminated.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a device of the class described, the combination of a revolvable cylindrical con-

verter shell mounted with its longitudinal axis of rotation horizontally disposed, a curved closure plate having its center of curvature substantially coincident with said axis of rotation and spaced from the shell, 70 a converter stack projecting laterally from said shell and extending through said plate and a hood having a lower end engaging said plate and positioned to receive the gases discharged from the shell through the converter stack.

2. In a device of the class described, the combination of a revolvable cylindrical converter shell mounted with its longitudinal axis of rotation horizontally disposed, a 80 cover plate carried by the converter shell and a hood having a lower open end engaging said closure plate to form a closed connection between the converter and hood.

3. In a device of the class described, the 85 combination of a revolvable cylindrical converter shell mounted with its longitudinal axis of rotation horizontally disposed and provided with a converter stack projecting from the side thereof, a hood adapted to receive the discharge from said stack, and a closure for the portion of the lower open end of the hood which is positioned outside of the converter stack.

4. In a device of the class described, the 95 combination of a revolvable cylindrical converter shell mounted with its longitudinal axis of rotation horizontally disposed and provided with a converter stack projecting from the side thereof, a hood adapted to receive the discharge from said stack, and a closure for the portion of the lower open end of the hood which is positioned outside of the converter stack, said closure being 100 spaced from the converter shell whereby distortion of the shell will not materially affect the form of the closure.

5. In a device of the class described, the combination of a cylindrical converter shell mounted to revolve about its longitudinal 110 axis and having a discharge opening in the side thereof, a hood mounted to receive the discharge from said opening, and means for providing a closed connection between the opening and hood, said means being spaced 115 from the converter shell thereby to insulate the same from distorting strains on the converter shell.

6. In a device of the class described, the combination of a cylindrical converter shell 120 mounted to revolve about its longitudinal axis and having a discharge opening in the side thereof, a hood mounted in fixed position to receive the discharge from said opening, and means carried by the converter shell 125 for closing the space between the converter shell and the adjacent end of the hood.

7. In a device of the class described, the combination of a cylindrical converter shell mounted to revolve about its axis and having 130

- a discharge opening in the side thereof, a hood mounted to receive the discharge from said opening, means for providing a closed connection between the opening and hood, 5 said means being spaced from the converter shell thereby to insulate the same from distorting strains on the converter shell, and means for supporting the hood in position engaging said closed connection means.
- 10 8. In a device of the class described, the combination of a cylindrical converter shell mounted to revolve about its axis and having a discharge opening in the side thereof, a hood mounted in fixed position to receive the 15 discharge from said opening, means carried by the converter shell for closing the space between the converter shell and the adjacent end of the hood, and means for supporting said adjacent end of the hood from said 20 converter shell whereby the converter and said means are permitted a revolving movement independent of the hood.
9. In a device of the class described, a cylindrical converter mounted to revolve 25 about its axis and a stationary hood supported directly on the side of the revolvable converter and adapted to receive discharges from the converter.
10. In a device of the class described, a cylindrical converter mounted to revolve 30 about its axis, a stationary hood supported directly on the side of the revolvable converter and adapted to receive discharges from the converter, and means tending to 35 maintain the hood in position relative to the converter.
11. In a device of the class described, a cylindrical converter mounted to revolve about its axis and provided with hood carrying 40 rings, a hood mounted in fixed position above the converter, and carrier wheels supporting said hood from said rings.
12. In a device of the class described, a cylindrical converter mounted to revolve 45 about its axis and provided with hood carrying rings, a hood mounted in fixed position above the converter, carrier wheels supporting said hood from said rings and equalizers connecting certain of said carrier wheels and 50 adapted to distribute the load of the hood on said rings.
13. In a device of the class described, a cylindrical converter mounted to revolve about its axis, a stationary hood supported 55 from the revolvable converter and adapted to receive discharges from the converter and equalizing means disposed between the hood and converter for distributing the weight of the hood on the converter.
- 60 14. In a device of the class described, a hood provided with a charging opening on one side thereof, a cover plate for closing said opening and means for moving said cover plate to and from a position closing 65 said opening.
15. In a device of the class described, a converter provided with a charging opening in a side thereof, a hood positioned to receive discharges from said opening, said hood provided with an opening leading to the opening 70 in the converter and a closure for said hood opening.
16. In a device of the class described, a converter provided with a charging opening in a side thereof, a hood positioned to receive 75 discharges from said opening, said hood provided with an opening leading to the opening in the converter, a closure for said hood opening, and means for substantially counterbalancing said closure.
17. In a device of the class described, a converter provided with a charging opening in a side thereof, a hood positioned to receive discharges from said opening, said hood provided with an opening leading to the opening 80 in the converter, a closure for said hood opening, a differential drum and a flexible connection between said drum and closure for moving the closure to and from its operative position.
18. In a device of the class described, a hood provided with an opening in the side thereof, a cable segment, a cover plate carried by said segment and adapted to close said opening and means engaging said segment to swing the cover plate to and from 85 its position closing said opening.
19. In a device of the class described, a hood provided with an opening in the side thereof, a pair of parallel arms, a beam connecting said arms to form a cover plate frame, and cover plates carried by said frame and adapted to close said opening.
20. In a device of the class described, a hood provided with an opening in the side 95 thereof, a pair of parallel arms, a beam connecting said arms to form a cover plate frame, cover plates carried by said frame and adapted to close said opening, and a curtain plate hung from said frame.
21. In a device of the class described, a hood provided with an opening in the side 105 thereof, a pair of parallel arms, a beam connecting said arms to form a cover plate frame, cover plates carried by said frame and adapted to close said opening, a curtain plate hung from said frame, and means for controlling said frame.
22. In a device of the class described, a hood provided with an opening in the side 115 thereof, a cover for said opening, a damper for controlling the flow through said hood and a single control for opening the damper simultaneously with the closing of said opening.
23. In a device of the class described, a cylindrical converter shell mounted to be revolved about its axis and provided with a plate carried by the shell and curved about 125 said axis as a center, a hood positioned above 130

- the shell and adapted to receive the discharges from said converter shell and a connection between said plate and hood adapted to close the space between the adjacent end 5 of the hood and said plate, said connection being flexible relative to the hood whereby accretions collecting within the hood may be removed therefrom when the converter is rotated.
- 10 24. In a device of the class described, a cylindrical converter shell mounted to be revolved about its axis and provided with a plate carried by the shell and curved about said axis as a center, a hood positioned above 15 the shell and adapted to receive the discharges from said converter shell and a curtain plate hung from the adjacent end of the hood and engaging said curved plate to close the space between the hood and plate.
- 20 25. In a device of the class described, a cylindrical converter shell mounted to be revolved about its axis and provided with a plate carried by the shell and curved about said axis as a center, a hood positioned above 25 the shell and adapted to receive the discharges from said converter shell and a curtain plate hung from the adjacent end of the hood and engaging said curved plate to close the space between the hood and plate,
- 30 30 said curtain plate being movable in the direction of rotation of the converter shell whereby accretions on the curved plate within the hood may be removed therefrom automatically by rotating the converter shell.
- 35 26. In a device of the class described, the combination of a rotary converter provided with an opening in the side thereof, a hood adapted to receive the discharge from said opening and a curtain plate disposed between the hood and converter designed substantially to close the interior of the hood from the entrance of outside air into the hood.
- 40 27. In a device of the class described, the combination of a rotary converter provided with an opening in the side thereof, a hood adapted to receive the discharge from said opening and a curtain plate disposed between the hood and converter designed substantially to close the interior of the hood from the entrance of outside air into the hood, said curtain being hung to swing about an axis parallel to the axis of rotation of the converter whereby the curtain may give in the direction of rotation of the converter.
- 45 28. In a device of the class described, the combination of a rotary converter provided with an opening in the side thereof, a hood adapted to receive the discharge from said opening, a curtain plate disposed between the hood and converter designed substantially to close the interior of the hood from the entrance of outside air into the hood, and means for supporting the curtain plate from the converter.
- 50 60 65 Signed at Tacoma, in the county of Pierce and State of Washington, this 9th day of July, A. D. 1917.
- CHARLES VAN AMBURGH.
